UNITED STATES PATENT OFFICE

150,028

DESIGN FOR A DISPLAY FIGURE

Addis Osborne, Chicago, Ill., assignor to Marshall Field & Company, Chicago, Ill., a corporation of Illinois

Application October 10, 1947, Serial No. 141,858

Term of patent 7 years

(Cl. D1—2)

To all whom it may concern:

Be it known that I, Addis Osborne, a citizen of the United States, residing in Chicago, in the county of Cook and State of Illinois, have invented a new, original, and ornamental Design for a Display Figure, of which the following is a specification, reference being had to the accompanying drawing, forming a part thereof:

In the drawing:

Figure 1 is a front perspective view of a display figure showing my new design, Figure 2 is a perspective view of the display figure shown in Figure 1; and Figure 3 is a rear perspective view of the figure shown in Figures 1 and 2.

I claim:

The ornamental design for a display figure, as shown.

ADDIS OSBORNE.
